UNITED STATES PATENT OFFICE.

SAMUEL B. GOFF, OF CAMDEN, NEW JERSEY.

HEATING DEVICE FOR STOVES, &c.

SPECIFICATION forming part of Letters Patent No. 599,419, dated February 22, 1898.

Application filed August 10, 1897. Serial No. 647,678. (No model.)

To all whom it may concern:

Be it known that I, SAMUEL B. GOFF, a citizen of the United States, residing in the city and county of Camden, State of New Jersey, 5 have invented a new and useful Improvement in Heating Devices for Stoves, Steam-Boilers, Furnaces, &c., which improvement is fully set forth in the following specification and accompanying drawings.

10 My invention relates to heating devices for stoves, steam-boilers, furnaces, &c.; and it consists of a novel manner of feeding and commingling the fluid combustible, air, and water employed in the proper proportions, 15 provision being also made for withdrawing the products of combustion and returning the same to the fire-chamber to be consumed therein.

It also consists of a novel construction of 20 commingling-chamber and its adjuncts, all the parts being readily assembled and disconnected according to requirements.

It further consists of novel details of construction, all as will be hereinafter fully set 25 forth, and particularly pointed out in the claims.

Figure 1 represents a vertical sectional view 30 of a heating device for a stove, &c., embodying my invention. Fig. 2 represents a section on line $\alpha\alpha$, Fig. 1. Fig. 3 represents a perspective view of a pan or receptacle supported above the fire-chamber, the same being provided with annular flues in the walls thereof. Fig. 4 represents a section on line yy , Fig. 3. 35 Fig. 5 represents a perspective view, partly in section, of a portion of the upwardly-extending flue seen in Figs. 3 and 4. Fig. 6 represents a perspective view of the commingling-chamber employed, in which the fluid combustible, air, and vaporized water are received and commingled. Fig. 7 represents a perspective view of the fire-chamber in detached position.

Similar letters of reference indicate corresponding parts in the figures.

Referring to the drawings, A designates a stove, the same consisting of a base B, which has the upwardly-extending outer walls C and the upright inner walls D, upon the up- 50 per edge of which is supported the rotary fire-

chamber E, the latter consisting of the base portion F, which is perforated or apertured to serve as a grate and having the upwardly-extending walls G.

H designates a depending journal which 55 extends from the bars F and is seated within the walls D.

J designates a receptacle or commingling-chamber and burner for the fluid combustible, said receptacle being in the present instance 60 of the shape of a hollow cross, which is supported upon the bars F, the sides K of said cross having openings L therein for the escape of the fluid combustible, as will be explained. The top M of the receptacle J is in the present instance removable and provided with the movable plate N', having the openings N, into which discharge the pipes P, Q, and R, which lead from the reservoirs S T U, respectively, 65 said reservoirs being adapted for the reception of a fluid hydrocarbon combustible, water, and compressed air.

V designates a branch pipe leading from the pipe P to a point below the grate F'. The said branch pipe serves to convey liquid hydrocarbon to a point beneath the grate.

W designates a pipe leading from the receptacle J to a thermometer or similar temperature-indicating device X, whereby the temperature of the contents of the receptacle 70 J can always be ascertained.

Y designates lugs projecting from the top M of the receptacle J, upon which is supported the pan or water-holding receptacle Z, the latter having the base A' and the upwardly-extending walls B', within which are formed the upright annular inclined flues or passages C', which are open at their bottoms and closed at their tops and sides, as will be understood from Figs. 1, 3, and 4, said passages discharging into the flues D', which extend upwardly at either side of the pan Z.

E' designates a flue into which the flues D' discharge, the products of combustion or a portion thereof being finally conducted into 85 the receptacle J through the flue F', while said products are also permitted to escape through the outlet G' at the upper ends of said flues.

H' and J' designate lids which are superimposed above each other, thereby forming the 90 100

oven K' therebetween, said lids being recessed to permit the passage of the flues D'.

The operation is as follows: In the space in the fire-chamber not occupied by the commingling-receptacle and burner is placed hard or similar fuel. The fire is started in the usual manner and its combustion may be aided by allowing the liquid hydrocarbon to escape from the pipe V beneath the grate and igniting the same. After the combustion of the hard fuel has progressed sufficiently the flow of liquid hydrocarbon from the pipe V can be checked. The products of combustion generated by the burning of the hard fuel in the fire-chamber heat the commingling-receptacle and burner J and also the pipes leading to the latter. The water and liquid hydrocarbon are thereby vaporized and the air heated. In the said receptacle and burner the heated air and vaporized water and hydrocarbon are mixed and pass through the openings L into the fire-chamber, where the mixture is consumed. After the fire has been started it can be fed by introducing hard fuel or the mixture of air and vapors, or both together, into the fire-chamber. The products of combustion are conducted away by means of the flues C' and D', a portion thereof passing into the commingling-chamber J, while the remainder escape through the opening G'. Access can be readily had to the interior by means of suitable doors, and the several flues, pipes, &c., can be provided with dampers, valves, &c., according to requirements.

The oven K' can be used for baking and the pan Z can be used for boiling water, &c.

In the preferred embodiment of my invention I locate an inverted funnel or conical-shaped shell at the junction of the flues D', the lower edge G² of said funnel serving to arrest any saturated steam in said flues D', said steam being condensed and returned through the flues E' to the commingling-chamber. It will also be apparent that more or less condensation will take place at or near the funnel or shell G² and that, if desired, I may employ extraneous condensing devices.

In the preferred embodiment of my invention the pan Z is provided with annular channels A², which can be utilized for boiling water or other fluids, said channels being more clearly seen in Fig. 3, since the same are removed from Fig. 1 for the sake of clearness of illustration. The flues D' are supported upon the feet D², which are sustained upon the brackets B², as will be understood from Fig. 1.

Having thus described my invention, what I claim as new, and desire to secure by Letters Patent, is—

1. A stove having a base, a bearing carried by said base, a fire-chamber for burning hard fuel mounted on said bearing, a commingling-receptacle and burner mounted in said fire-

chamber adapted to heat air and vaporize liquid hydrocarbon and water introduced into said receptacle and burner and said receptacle having openings adapted to introduce the mixed vapors and air into said fire-chamber, reservoirs for holding water and liquid hydrocarbon, pipes leading from said reservoirs through said fire-chamber into said receptacle and burner, and means for introducing air into said receptacle and burner. 75

2. A stove having a base, a bearing carried by said base, a fire-chamber for burning hard fuel mounted on said bearing, a commingling-receptacle and burner mounted in said fire-chamber adapted to heat air and vaporize liquid hydrocarbon and water introduced into said receptacle and burner and said receptacle and burner having openings for introducing the mixed vapors and air into said fire-chamber, reservoirs for liquid hydrocarbon and water, pipes leading from said reservoir through said fire-chamber into said receptacle and burner, means for carrying air into said receptacle and burner, and a pipe leading from one of said pipes to a point beneath the fire-chamber. 80

3. A stove, a fire-chamber for burning hard fuel supported in said stove, a commingling-receptacle and burner mounted in said fire-chamber adapted to heat air and vaporize liquid hydrocarbon and water and to introduce the mixture into said fire-chamber, means for supplying said receptacle and burner with air, liquid hydrocarbon and water, a flue leading from said fire-chamber and having a discharge-opening at its upper end, and a return-pipe leading from said flue into said receptacle and burner. 95

4. A stove, a fire-chamber for burning hard fuel supported in said stove, a commingling-receptacle and burner mounted in said fire-chamber adapted to heat air and vaporize liquid hydrocarbon and water and to introduce the mixture into said fire-chamber, means for supplying said receptacle and burner with air, liquid hydrocarbon and water, a water-holding pan supported above said receptacle and burner, and flues leading from said fire-chamber through said pan. 105

5. A stove, a fire-chamber for burning hard fuel supported in said stove, a commingling-receptacle and burner mounted in said fire-chamber adapted to heat air and vaporize liquid hydrocarbon and water, and to introduce the mixture into said fire-chamber, means for supplying said receptacle and burner with air, liquid hydrocarbon and water, a water-holding pan supported above said receptacle and burner, an oven mounted above said pan, and flues leading from said fire-chamber through said pan and oven. 115

6. A stove, a fire-chamber for burning hard fuel supported in said stove, a commingling-receptacle and burner mounted in said fire-chamber adapted to heat air and vaporize liquid hydrocarbon and water, and to introduce the mixture into said fire-chamber, means for supplying said receptacle and burner with air, liquid hydrocarbon and water, a water-holding pan supported above said receptacle and burner, an oven mounted above said pan, and flues leading from said fire-chamber through said pan and oven. 125

uid hydrocarbon and water, and to introduce the mixture into said fire-chamber, means for supplying said receptacle and burner with air, liquid hydrocarbon and water, a water-holding pan supported above said receptacle and burner, an oven mounted above said pan, annular flues passing through said pan, and

flues leading from said annular flues through said oven.
